CLAIM

The ornamental design for a talar resection guide, shown and described.

DESCRIPTION

FIG. 1 is a side elevational view of a talar resection guide, showing my new design;

FIG. 2 is a bottom plan view thereof;

FIG. 3 is a top plan view thereof;

FIG. 4 is a front elevational view thereof;

FIG. 5 is a rear elevational view thereof; and

FIG. 6 is a perspective view thereof.
